UNITED STATES PATENT OFFICE.

JOHN C. KINLEY, OF RICHMOND, INDIANA.

HOT-AIR ATTACHMENT FOR STOVES.

SPECIFICATION forming part of Letters Patent No. 711,053, dated October 14, 1902.

Application filed February 17, 1902. Serial No. 94,445. (No model.)

To all whom it may concern:

Be it known that I, JOHN C. KINLEY, a citizen of the United States, residing at Richmond, in the county of Wayne, and in the 5 State of Indiana, have invented and produced a new and useful Improvement in Hot-Air Attachments for Stoves, of which the following is a specification, which is sufficiently clear and concise to enable others skilled in the 10 art to which it appertains to make and use the same.

My invention relates to hot-air attachments for stoves, and has for its object the provision of an arrangement of the several parts thereof 15 whereby air of a low degree of temperature is drawn therein and discharged therefrom at a higher degree of temperature.

Another object is the provision of an attachment to be used in connection with ordinary stoves or furnaces whereby cool air is taken by the action of the heat in the stove from underneath the stove near the floor or from any other point on the floor of a room, passed through the fire-space in the stove, 25 and then discharged therefrom at a high degree of temperature into the same or another room or into a room above.

Another object is to provide means for equalizing the temperature in all parts of a 30 room with a minimum of fuel.

Another object is to utilize a portion of the heat from a stove that otherwise would pass out through the flue in drawing the cool air from various parts of the room and then 35 turning it again at a higher degree of temperature; and another object is the provision of an attachment, as specifically described elsewhere herein, which in addition to accomplishing the above-enumerated objects 40 will be neat and attractive in appearance, positive and effective in its operation, and which can be manufactured and sold at a very low price.

Other objects and advantages will appear 45 from the following specification and from the drawing forming a part thereof.

The invention consists in hot-air attachments for stoves embodying certain novel features and details of construction and relative disposition of the several parts, as hereinafter particularly set forth, illustrated in 50

the drawing, and incorporated in the claims hereunto appended.

With the above-enumerated objects in view I will now refer to the accompanying drawing, 55 which forms a part of this specification, which is a view of a vertical section of my attachment and its relative position with reference to a stove and the floor of a room.

In the drawing the numerals refer to the 60 various parts of my invention and the letters refer to the parts shown simply to illustrate the relative locations of the various parts of my invention.

a' and *a*'' represent the sides of an ordinary 65 stove, *b* the top, and *c* the bottom thereof.

d represents the vent for the escape of smoke and gases from the stove into the flue.

e represents the floor of a room on which the stove rests, and *X* represents the fire- 70 space in the stove.

Referring now to my invention, 10 represents a drum, preferably of one piece of material—such, for instance, as metal tubing—with threaded ends and a threaded aperture 75 in the center of a size sufficient to receive the threaded lower end of the pipe 22. Each end of the drum 10 is provided with reducing-fittings 11' and 11'', which fit over the ends of 10, respectively. The outer ends of 11' and 80 11'' are threaded on the outside, to which are secured the elbows 12' and 12'', as shown.

13' and 13'' represent perpendicular pipes with threaded ends, the upper ends fitting into the respective elbows 12' and 12'', as 85 shown. The threads on the lower ends of 13' and 13'' continue twice the distance on the pipes as do the threads on the upper ends thereof.

14' and 14'' represent lock-nuts surrounding 90 the respective pipes 13' and 13'' and rest on the upper surface of the bottom *c* of the stove.

15' and 15'' represent couplings which are screwed on the lower ends of the respective pipes 13' and 13'' and engage the under surface of *c*. 95

16' and 16'' represent inverted funnels terminating in threaded nipples, which are screwed into the respective couplings 15' and 15''. 100

In assembling the above-enumerated parts I first take the drum 10 and screw onto its

ends the reducers 11' and 11". I then screw the elbows 12' and 12" onto the ends of the respective reducers. The upper ends of the pipes 13' and 13" are then screwed into the 5 elbows 12' and 12". The lock-nuts 14' and 14" are then screwed onto the lower ends of 13' and 13". I then pass the lower ends of 13' and 13" through corresponding holes provided in the bottom *c* of the stove for that 10 purpose, so that the lower ends of 13' and 13" will project through the bottom *c*. The couplings 15' and 15" are then screwed onto the lower ends of 13' and 13" until they contact with the bottom *c*. The funnels 16' and 16" 15 are then screwed into the respective couplings 15' and 15", and I then screw the lower end of the pipe 22 into the aperture in the center of the drum 10, when the device will be ready for operation.

20 It will now be apparent that should a fire be maintained in the space X the pipes 13' and 13" and the drum 10 will be heated thereby and without interfering with or detracting from the usual amount of heat radiating 25 to the sides and top of the stove. As the parts of my attachment located inside the stove become heated the air therein becomes heated and will pass up through the pipe 22 into the room at a point above the stove or 30 elsewhere to wherever the pipe 22 may lead. The hot air passing upward, as stated, the cool air from below the stove will be taken up through the funnels to take its place, and a circulation will thus be established and will 35 be maintained as long as the drum and the pipes are warmer than the air at the inlets.

My invention is perfectly adapted to accomplish the results for which it is intended, and it is evident that changes in and modifications 40 of the specific construction herein shown and described may be made and that analogous parts may be used to accomplish the same results without departing from the spirit of my invention or sacrificing any of its many 45 advantages, and the specific construction of the details of my invention in which novel features are embodied may be variously changed without altering the essential principles, which are claimed as new.

50 Having shown and fully described my invention, what I claim, and desire to secure by Letters Patent, is—

1. A hot-air attachment for stoves comprising

ing a horizontal drum 10, located in the upper portion of the fire-space of a stove, in combination with the reducing-fittings 11" and 11' attached to each end of the drum, the elbows 12' and 12" attached to said reducing-fittings, the perpendicular pipes 13' and 13" secured in the said elbows and extending 55 down through the bottom of the stove and held rigidly in place by the lock-nuts 14' and 14" resting on the upper surface of the stove-bottom in connection with the couplings 15' and 15" pressing in the opposite direction 60 against the bottom of the stove, all substantially as shown and described.

2. A hot-air attachment for stoves comprising an exit-pipe 22 and a horizontal drum 10, located in the upper portion of the fire-space 70 of a stove, in combination with the reducing-fittings 11' and 11" attached to each end of the drum, the elbows 12' and 12" attached to said reducing-fittings, the perpendicular pipes 13' and 13" secured in the said elbows and 75 extending down through the bottom of the stove and held rigidly in place by the lock-nuts 14' and 14" resting on the upper surface of the stove-bottom in connection with the couplings 15' and 15" pressing in the opposite 80 direction against the bottom of the stove, all substantially as shown and described.

3. A hot-air attachment for stoves comprising a horizontal drum 10, located in the upper portion of the fire-space of a stove, in combination with the reducing-fittings 11' and 11" 85 attached to each end of the drum, the elbows 12' and 12" attached to said reducing-fittings, the perpendicular pipes 13' and 13" secured in the said elbows and extending down 90 through the bottom of the stove and held rigidly in place by the lock-nuts 14' and 14" resting on the upper surface of the stove-bottom in connection with the couplings 15' and 15" pressing in the opposite direction against 95 the bottom of the stove and receiving-funnels 16' and 16" suspended from said couplings, all substantially as shown and described.

In testimony whereof I have hereunto subscribed my name in the presence of two subscribing witnesses.

JOHN C. KINLEY.
